UNITED STATES PATENT OFFICE.

ANTONIO C. PESSANO, OF PHILADELPHIA, PENNSYLVANIA, ASSIGNOR TO
THE GEORGE V. CRESSON COMPANY, OF SAME PLACE.

DESIGN FOR A BRACKET OR POST HANGER FOR JOURNAL-BOXES.

SPECIFICATION forming part of Design No. 32,586, dated April 24, 1900.

Application filed March 19, 1900. Serial No. 9,338. Term of patent 14 years.

To all whom it may concern:

Be it known that I, ANTONIO C. PESSANO, of the city and county of Philadelphia, in the State of Pennsylvania, have invented a new and original Design for a Bracket or Post Hanger for Journal-Boxes, of which the following is a specification.

My new and original design for bracket or post hangers for journal-boxes is shown in the accompanying drawings, in which—

Figure 1 is a side elevation of a bracket-hanger embodying the design, and Figs. 2 and 3 are respectively an end elevation and a top or plan view of the same.

15 A A are two oppositely-curved arms bent toward one another and terminating in flat ends $\alpha \alpha$, which are united by a connecting web B.

C is a frame at the outer ends of the arms A A, and consisting of the upright sides c c, the arched top b, and the transverse base d, forming an arched frame in the plane of the arms.

20 f f are ribs extending centrally along the inner and outer faces of the arms A A.

f' is a continuation of one of the ribs f over the arched top b of the frame C and is surmounted at the top by a central boss g.

H H are enlarged ribs extending longitudinally upon the outer faces of the lower portions of the sides c c, terminating in flattened heads h h.

The boss g at the top of the frame C is continued upon the inner side at g', and I is a boss on the base d, projecting on both sides 35 and located opposite to the boss g g'.

K K are bosses on the ends $\alpha \alpha$ of the arms A, from which the outer ribs f f extend.

The essential features of the design are the oppositely-curved arms A A, carrying the 40 arched frame C, composed of the arched top b, the sides c c, and the base d, with the enlarged longitudinal ribs H H on the outer faces of the lower portions of the sides c c.

What I claim as new, and desire to secure 45 by Letters Patent, is as follows:

The design for a bracket or post hanger for journal-boxes, substantially as described and as shown in the accompanying drawings.

In testimony of which invention I have 50 hereunto set my hand.

ANTONIO C. PESSANO.
